(57) **CLAIM**

The ornamental design for a combined trash and recycling receptacle, as shown and described.

DESCRIPTION

FIG. 1 is a perspective view of a combined trash and recycling receptacle having a first bottom section of the present invention;

FIG. 2 is a first side view of the receptacle of FIG. 1;

FIG. 3 is a second side view of the receptacle of FIG. 1;

FIG. 4 is a third side view of the receptacle of FIG. 1;

FIG. 5 is a fourth side view of the receptacle of FIG. 1;

FIG. 6 is top view of the receptacle of FIG. 1;

FIG. 7 is a bottom view of the receptacle of FIG. 1;

FIG. 8 is a perspective view of the receptacle having a second bottom section of the present invention;

FIG. 9 is a first side view of the receptacle of FIG. 8;

FIG. 10 is a second side view of the receptacle of FIG. 8;

FIG. 11 is a third side view of the receptacle of FIG. 8;

FIG. 12 is a fourth side view of the receptacle of FIG. 8;

FIG. 13 is top view of the receptacle of FIG. 8; and

FIG. 14 is a bottom view of the receptacle of FIG. 8.

FIG. 15 is a perspective view of the receptacle having a second top section of the present invention;

FIG. 16 is top view of the receptacle of FIG. 15.

FIG. 17 is a perspective view of the receptacle having a second top section and the second bottom section of the present invention.

FIG. 18 is a top view of the receptacle of FIG. 17.

FIG. 19 is a perspective view of the receptacle having a third top section and a first bottom section of the present invention;

FIG. 20 is a top view of the receptacle of FIG. 19.

FIG. 21 is a perspective view of the receptacle having a third top section and a second bottom section of the present invention; and,

FIG. 22 is a bottom view of the receptacle of FIG. 21.

The broken lines showing additional features of the combined trash and recycling receptacle are for illustrative purposes only and form no part of the claimed design.
